COWLED SWIVEL CASTER

James J. Modarelli, Middleburg Heights, Ohio

Application April 3, 1956, Serial No. 40,892

Term of patent 14 years

(Cl. D10—6)

Fig. 1.

Fig. 2.

Fig. 3.

Fig. 4.

Fig. 1 is a side elevational view of a cowled swivel caster, showing my new design;

Fig. 2 is a rear elevational view of the cowled swivel caster of Fig. 1;

Fig. 3 is a front elevational view of the cowled swivel caster of Fig. 1; and

Fig. 4 is a plan view of the caster of Fig. 3.

I claim:

The ornamental design for a cowled swivel caster as shown.
